UNITED STATES PATENT OFFICE.

EDWARD WESTON, OF NEWARK, NEW JERSEY.

REFLECTING-GALVANOMETER.

SPECIFICATION forming part of Letters Patent No. 730,061, dated June 2, 1903.

Application filed July 9, 1902. Serial No. 114,941. (No model.)

To all whom it may concern:

Be it known that I, EDWARD WESTON, a subject of the King of Great Britain, residing at Newark, in the county of Essex and State 5 of New Jersey, have made a new and useful Invention in Reflecting-Galvanometers, of which the following is a specification.

My invention is directed particularly to improvements in reflecting-galvanometers in which the movable coil is supported by a filar suspension; and it has for its objects, first, to so construct those parts of the instrument which support the field-magnet and the movable coil that the latter will always maintain 10 a definite relation to the magnetic field through which it moves when the instrument is leveled, adjusted, and ready for use; second, to provide novel means for supporting the field-magnet of the instrument in connection with the casing or cover, the same being so devised that said magnet may be 15 readily detachable and will always bear a fixed or definite relation to the movable coil which controls the movement of the mirror; third, to provide novel means for effecting 20 the circuit connections between the terminals and the coil, the same being so arranged that when the coil, its core, and the coil and core supports, together with the mirror, constituting what I term the "movement," are removed as a unit from the instrument the circuit is interrupted between the fixed terminals carried by the movement and yielding 25 terminals carried by the casing or cover; fourth, to provide novel means for lifting and 30 securing the coil against rotary movement and from support by the filar suspension when the instrument is not in use.

For a full and clear understanding of the 35 invention, such as will enable others skilled in the art to construct and use the same, reference is had to the accompanying drawings, in which—

Figure 1 is a longitudinal sectional view of 40 the instrument, taken through the body thereof on the line X X, Fig. 4, a part of the field-magnet clamp, the binding-posts, the spirit-level, the filar suspension, the mirror, and two of the leveling-screws being shown in 45 side elevational view. Fig. 2 is a side elevational view of the movement detached from 50 the instrument and as seen looking at this

part as shown in position in Fig. 1 from right to left. Fig. 3 is a transverse sectional view taken through Fig. 1 on the line Y Y, a part 55 of the cover being broken away, so as to show the interior structure. Fig. 4 is a plan view as seen looking at Fig. 1 from the bottom toward the top of the drawing, the casing of the instrument, however, being removed in 60 this view for the purpose of showing the entire interior structure. Fig. 5 is a detail view illustrating the means for supporting the coil and the mirror.

In the construction of delicate electrical 65 measuring instruments, such as reflecting-galvanometers, where the movable coil, its filar suspension, and the mirror carried thereby are removable as a unit from the body of the instrument it is important that the coil 70 and the magnetizable core which it surrounds shall bear a definite or fixed relation to the poles of the field-magnet when the movement is in place and that the coil should move when the instrument is leveled 75 and adjusted freely in the air-space between the poles of the field-magnet and the magnetizable core. It is also important that the field-magnet itself be so secured to the casing 80 of the instrument as to bear always a constant relation thereto, so that when it is once secured in place within the casing the movement may be removed at any time and restored, with the assurance that the instrument will perform its functions with cer- 85 tainty and accuracy.

With instruments of this type owing to the delicacy of the movable parts it is always necessary to lift the movable coil and the mirror, so that their weight shall be taken 90 off the delicate filar suspension and that the coil shall be so locked or held that it will not have a tendency to move from its normal position about the core. It is also important that the electrical connections between the 95 coil and the binding-posts of the instrument shall be as simply and compactly arranged as possible, so that accurate results shall always be obtained. It was with these special objects in view that the improvements 100 embodied in the present invention were conceived and reduced to practice by me.

Referring now to the drawings in detail, in all of which like letters and numerals of ref-

erence represent like parts wherever used, *c* represents the casing of the instrument, made, preferably, of some non-magnetic metal, as brass, and of the conformation shown, said casing being provided with three or more detachable legs *l*, slotted at their outer ends for the purpose of receiving the usual leveling-screws.

a represents the lid or cover thereof, which is secured and accurately fitted to the upper edge of the casing by a number of screws. This cover is made also of non-magnetic metal and is provided at its axial center with a downward extension, in which is drilled a hole adapted to receive a screw *s* for the purpose of securing the field-magnet in place.

m represents the permanent field-magnet, made, preferably, of cylindrical form, as shown in Figs. 3 and 4, and having drilled in its upper surface three holes or openings, in which are secured soft-metal plugs *e*, preferably of iron, said plugs being, in effect, integral with the magnet and having drilled in their upper ends cone-shaped holes for the purpose of receiving the coned ends of three metal pins *p*, secured directly to the under surface of the casing.

t represents a metallic clamp of tripod nature, the outer ends of the legs of which are accurately planed off, so as to rest when in position against the lower surface of the field-magnet *m*, said clamp being provided at its center with an opening, through which the screw *s* is adapted to pass. The length of the cone-shaped pins *p* is such and they are so secured to the under surface of the lid or cover *a* that when the magnet is held in place by the screw *s* and clamp *t* in the manner shown its opposite faces will be in planes parallel with the trued face of the lid or cover secured to the upper edge of the casing for the purpose of assuring mathematical accuracy between the coil of the movement and the magnetic field through which it moves.

g is a spirit-level of well-known form, and *b* are binding-posts, all secured in the upper surface of the lid or cover. In one side of the lid or cover is constructed an accurately-turned opening having a definite relation to the poles of the field-magnet *m*, the inner cylindrical surface of said opening being turned in a lathe, so as to be practically concentric with the curved portions of the field-magnet poles. (See Figs. 3 and 4.)

55 *g* is a mirror-chamber having substantially the conformation shown in Fig. 2 and having cast integral therewith a downwardly-cylindrical portion provided with a flange, as shown, and a still further downwardly-extending portion *h*, the lower end of which extends substantially at right angles to the body portion, so as to act as a support for the lower pivotal part of the movable coil *q*. To the upper end of the mirror-chamber is secured by insulating-joints the usual double-adjusting suspension-tubes *v*, made of metal and

provided at their upper ends with a rod *x*, to which is secured the filar suspension *f*.

y is an adjusting-screw for regulating the movement of the rod, and hence the vertical adjustment of the coil *q*.

q is the movable coil, which is constructed substantially like the similar part disclosed in United States Patent No. 611,722, granted to me on the 4th day of October, 1898, the pivot-plates *6* in the present instance, however, being attached the lower one directly to a spiral spring *r*, expansible in the direction of its length, with its lower end connected directly to a conducting-pin *u*, located in the axial center of a hard-rubber or other insulating-sleeve *i*, detachably secured by a screw *j* in the slotted end of the core-support *h*, and the upper one to a rigid metallic standard *o*, the upper end of which is connected directly to the lower end of the filar suspension *f*. This rigid metallic standard *o* also acts as a support for the mirror *n*, which is located directly in the rear of an opening in the mirror-chamber, provided with a glass or other transparent medium, as is usual in such instruments.

k represents the magnetizable core, which is located with its axis in the axial line of the magnetic field between the curved pole-pieces of the permanent magnet *m*. This core is secured directly to the core-support *h* by dowel-pins and one or more screws, as shown.

w represents an insulated conductor secured at its upper end to the inner of the tubes *v* and extending thence directly to a contacting pin *1*, constituting a fixed terminal, secured to and insulated from the under surface of the cylindrical portion of the mirror-chamber and adapted to rest when in position with its free end upon one of the springs or yielding terminals *7*, (see Fig. 4,) connected to one of the binding-posts *b*, insulated from the lid or cover of the instrument. The other binding-post *b* is similarly insulated and is provided with a similar spring or yielding terminal *7*, the free end of which is adapted to rest against another conducting-pin *2*, constituting a second fixed terminal, carried by and insulated from the mirror-chamber, said conducting-pin being connected by a continuance of the conductor *w* to the pin *u*, which in turn is connected directly to the coil *q* through the lower pivot-plate *6*, the upper pivot-plate *6*, connected also to the coil, being connected directly through the standard *o*, filar suspension *f*, and rod *x* to the tube *v*.

Near the lower end of the downwardly-extending portion *h*, which constitutes the core-support, is a lug or extension *9*, provided with a hole or opening adapted to receive an upwardly-extending rod *z*, which passes through a similar opening in the base of the mirror-chamber and is provided with a laterally-extending arm *3*, adjustably secured to

it, with its outer end bent back upon itself and constituting a delicate yielding means for lifting the coil *q* and locking or holding it against movement and at the same time 5 lifting the mirror and all of the attached parts, so that the filar suspension *f* is relieved of their weight.

4 is a spiral spring which surrounds the rod *z*, with its lower end resting against the 10 lug or extension 9 and its upper end against a pin 10, carried by the rod.

5 is an operating cam or eccentric pivotally supported by the mirror-chamber, with its operating end resting against the upper 15 end of the rod *z*.

In the construction of this instrument, as before indicated, the opening in the lid or cover *a*, which receives the movement, is turned in a lathe with mathematical nicety, 20 and the permanent field-magnet *m* is supported by the tripod clamp *t*, screw *s*, soft-metal plugs *e*, and cone-shaped pins *p* in such manner that the axial line of the magnetic field of the curvilinear pole-pieces passes 25 through the mathematical center of the cylindrical opening in the lid. In like manner the magnetizable core *k* is turned with such exactness and so supported by the dowel-pins and screw that its axis coincides with the before-mentioned axes and that the air-spaces between its curvilinear surfaces and the curved 30 poles of the field-magnet are symmetrical in every particular. In like manner the cylindrical portion of the mirror-chamber and the face-flange thereof, together with the upper 35 surface of the lid at this point, are so turned in a lathe that when all of the parts are secured finally in position the axial lines of the magnetic field of the magnetizable core 40 *k*, the coil *q*, and the filar suspension *f* are in absolute coincidence when the instrument is properly leveled and adjusted. This feature of mathematical adjustment constitutes an 45 important element in my invention, the structural arrangement being such that the movement, embracing the parts shown in Fig. 2, may be withdrawn from the instrument at any time for adjustment or repairs and again restored with the absolute assurance that all 50 of the parts of the instrument will preserve their original relation to each other.

As shown in Figs. 1 and 2, the instrument is ready for use with the coil *q* in its lower 55 position and the cam or eccentric 5 in a vertical position, thus forcing the rod *z* to its lower position against the stress of the spring 4. When it is desired to move the instrument or disturb it in any way, it is only necessary to rotate the cam or eccentric 5 from left to right 60 in the direction of the arrow, (see Fig. 2), when the spring 4 will cause the rod *z* and arm 3 to be lifted, and hence to lift also the coil *q*, standard *o*, and mirror *n*, so that the lower end of the coil will come into mechanical 65 contact with the lower end of the magnetizable core *k* and be locked or maintained

against movement or rotation, and the weight of these parts will, for like reason, be removed from the delicate filar suspension *f*.

Although the present invention is directed especially to improvements in reflecting-galvanometers, I do not limit all of the features thereof to use in connection with such instruments, as obviously a number of the features embodied in this invention may have a general use in connection with electrical measuring instruments or in connection with other instruments of precision where it is desirable to have a mathematical relation of parts when assembled for operation, and my claims are generic as to all such uses or adaptabilities. To make a single illustration, the manner of sustaining or supporting the permanent field-magnet *m* in connection with the lid or cover of the instrument through the agency of a clamp 85 may be applied with equal practicability to the case of the instrument directly and for use in connection with electrical measuring instruments generally; nor do I limit this feature of the invention to the use of a single 90 clamp *t* when combined with the means of support with the lid or the case in the nature of soft-metal plugs and cone-shaped steady or centering pins *p*, as my claims are designed to be of such scope as to include 95 all such obvious uses and modified forms. I wish it also understood that by the term "movement" used throughout the specification and in the claims hereinafter I mean the movable part of an electrical measuring instrument and the adjunct parts connected thereto and adapted to be removed therewith from the body of the instrument as a unit, the same constituting either a coil and the indicating parts adapted to be moved thereby or any magnetizable movable agent, as an 100 armature, adapted to be acted upon by a magnetic field closely surrounding the same or closely adjacent thereto.

I make no claim in the present application 110 to a permanent field-magnet having soft masses embedded in its faces for the purpose of affording a means of support therefor, as this feature constitutes in part the subject-matter of another application filed by me in 115 the United States Patent Office on the 7th day of May, 1902, and bearing Serial No. 106,242. In the before-mentioned application I have also claimed a permanent magnet having soft 120 masses embedded in its face in combination with steady or centering pins or means for definitely locating the magnet with relation to the casing, said parts being held together by the binding action of the lid or cover of the instrument when secured in place. 125

My claims in the present application, in so far as they relate to this feature, are directed, broadly, to a permanent magnet having soft masses embedded in its face, together with steady or centering pins or means secured to 130 the lid or casing and one or more clamps for securing the magnet firmly in position.

Having thus described my invention, what I claim, and desire to secure by Letters Patent of the United States, is—

1. A reflecting - galvanometer having its field-magnet secured directly to the lid or cover of the instrument and in a fixed or definite relation thereto; in combination with a detachable "movement" consisting of a suspended mirror and coil and a magnetizable core and supports therefor, so secured in the lid or cover that the axes of the magnetizable core, the movable coil and the support for the latter are coincident when the instrument is leveled, substantially as described.
- 15 2. A reflecting - galvanometer having its field-magnet detachably secured to the lid or cover; in combination with a "movement" having a magnetizable core, a movable coil and a mirror; together with a mirror - chamber and supports for the coil, the mirror and the magnetizable core operatively connected to the mirror-chamber, the latter being provided with a downwardly-extending cylindrical portion adapted to fit in an opening in the lid or cover and a flange adapted to rest upon the upper surface thereof, said parts being relatively so constructed that the axial lines of the magnetic field, the magnetizable core, the coil and its support are coincident when the instrument is leveled, substantially as described.
- 25 3. A reflecting-galvanometer provided with a field-magnet and a "movement" both secured to the lid or cover of the instrument; together with binding-posts operatively connected to yielding terminals; in combination with fixed terminals carried by the "movement" and electrically connected with the coil thereof, said fixed terminals being adapted to make good electrical contact with the yielding terminals, when the "movement" is secured in place, substantially as described.
- 35 4. An electrical measuring instrument provided with a field-magnet and means for maintaining it in a definite relation to the lid or cover; in combination with a clamp having a series of legs and adapted to firmly secure the magnet against the before-mentioned means, substantially as described.

5. An electrical measuring instrument provided with a field-magnet having soft masses embedded in one of its faces; in combination with a lid or cover for the instrument provided with steady or centering pins adapted to rest in centering-holes in the before-mentioned masses; together with a clamp or clutch adapted to secure the magnet to the lid or cover and in a definite relation thereto, substantially as described.

6. An electrical measuring instrument provided with a casing and a lid or cover therefor; in combination with a field-magnet secured directly to the under surface of the lid or cover by a clamp; together with a "movement" embracing a magnetizable core, a coil and supports therefor, the relative construction of the several parts being such that when the "movement" is in position the axes of the magnetic field, the core and the coil are substantially coincident, substantially as described.

7. Means for lifting the coil and mirror of a reflecting-galvanometer into their upper positions, consisting of a rod having an arm extending laterally beneath the upper end of the coil and a spring adapted normally to hold the rod in its upper position; together with means for locking the rod in its lower position, substantially as described.

8. A reflecting-galvanometer provided with a movable coil and mirror secured thereto; in combination with means for lifting the coil and the mirror off their support and locking them against movement, said means consisting of a vertically-moving rod provided with an arm extending laterally beneath the upper end of the coil and a spring tending normally to lift the rod into its upper position; together with an eccentric or cam adapted to force the rod into its lower or inoperative position, substantially as described.

In testimony whereof I have signed my name to this specification in the presence of two subscribing witnesses.

EDWARD WESTON.
